UNITED STATES PATENT OFFICE.

NAPOLEON RANCOUR, OF HIGHLAND PARK, MICHIGAN.

BURGLARPROOF LOCK.

Application filed May 10, 1922. Serial No. 559,710.

To all whom it may concern:

Be it known that I, NAPOLEON RANCOUR, a citizen of the United States of America, residing at Highland Park, in the county of Wayne and State of Michigan, have invented certain new and useful Improvements in Burglarproof Locks, of which the following is a specification, reference being had therein to the accompanying drawings.

This invention relates to burglar-proof locking devices for use in connection with locks having a sliding bolt for the locking element.

An object of the invention is to provide a reliable and efficient device which will operate automatically to retain the bolt of the lock in extended or locked position.

Another object is to provide a device which can be readily applied to any door, window or the like and when applied will be in a position on the door or window which will preclude any possibility of an unauthorized person withdrawing the bolt from its keeper to unlock the door or window.

Another object is to provide a strong and durable device which can be manufactured at a very low cost.

With the above and other objects in view, the invention consists of certain novel features of construction as will be more fully described and particularly pointed out in the appended claims.

In the accompanying drawing:

Figure 1 is a perspective view of the locking device applied to a door;

Figure 2 is a detail sectional view taken on the line 2-2 of Figure 1;

Figure 3 is a detail view of the plunger;

Figure 4 is a detail view showing a slightly modified form of construction;

Figure 5 is a detail view of the plunger illustrated in Figure 4.

Referring now to the drawings in which like characters of reference designate corresponding parts throughout the several views, the numeral 1 designates a door having a recess formed in the outer edge thereof which receives a lock 2 having a sliding bolt 3 adapted to engage a keeper 4. The bolt 3 is actuated by suitable mechanism within the lock which is controlled by a key 5.

A plunger 6, preferably of steel, extends through aligned openings 7 and 8 respectively in the door 1 and lock 2 and is normally in engagement with the adjacent side of the

bolt. The plunger is also adapted to engage a recess 9 formed in the bolt 3 intermediate the ends thereof when the bolt is in extended or locked position. The outer end of the plunger 6 is reduced to provide an annular shoulder 10 and is threaded as shown at 11.

A flat spring 12 of any suitable material is removably secured to the door adjacent to the outer edge thereof and is provided with an opening 13 at its upper end which receives the threaded outer end of said plunger. A knurled nut 14 engages the threaded portion of said plunger to retain the upper end of said spring in engagement with the annular shoulder 10 whereby the plunger is normally urged inwardly under tension of the spring. A headed pin 15 passes through an opening 16 in the spring adjacent to the upper end thereof and is removably secured to the door to limit the outward movement of the spring.

In the modification illustrated in Figure 4, a plunger 20 is threaded at its outer end as shown at 21. A flat spring 22 is removably secured to the door adjacent the outer edge thereof, and is provided with an opening in the upper end thereof which receives the threaded outer end of the plunger. An interiorly threaded metallic washer 23 and a knurled nut 24 are adjustably mounted on the threaded outer end of the plunger upon opposite sides of the spring. With this construction, the tension of the spring can be regulated by adjusting the washer and nut on the threaded outer end of the plunger to vary the distance between the upper end of the spring and the door when the bolt is in retracted or unlocked position.

In use, when the key 5 is operated, the lock mechanism will move the bolt outwardly into engagement with the keeper to assume a locked position whereupon the recess 9 in the bolt will register with the aligned openings 7 and 8 respectively. The plunger 100 acting under the influence of the spring will then move inwardly into engagement with the recess 9 thus retaining the bolt in locked position. When it is desired to unlock the door, the knurled nut is pulled outwardly 105 to disengage the plunger from the recess 9 in the bolt whereupon the key may be operated for withdrawing the bolt from its keeper.

Whenever for any reason it is desired to 110 render the plunger inoperative a curved wedge-shaped member 25 is pivotally

mounted upon the door above the plunger. The lower free end of the wedge-shaped member is adapted to extend between the spring and door to retain the plunger in 5 outermost position.

While it is believed that from the foregoing description the nature and advantages of the invention will be readily apparent, I desire to have it understood that I do not 10 limit myself to what is herein shown and described, and that such changes may be resorted to when desired as fall within the scope of what is claimed.

What I claim as my invention is:

15 1. The combination with a lock having a sliding bolt, of a reciprocatory plunger, spring means for moving said plunger into engagement with said bolt to retain the same in locked position, and movable means engageable with said spring means for retaining said plunger out of engagement with said bolt.

20 2. The combination with a lock having a sliding bolt, of a reciprocatory plunger, spring means for moving said plunger into engagement with said bolt to retain the same in locked position, and a pivoted member engageable with said spring means for retaining said plunger out of engagement with 25 said bolt.

30 3. The combination with a lock having a sliding bolt, of a plunger, spring means for moving said plunger inwardly into engagement with said bolt to retain the same in locked position, means for moving said plunger outwardly to disengage the same from 35 said bolt to permit the latter to return to unlocked position, and means extending through said spring means for limiting the outward movement of said plunger.

40 4. The combination with a lock having a sliding bolt, of a plunger, spring means for moving said plunger inwardly into engagement with said bolt to retain the same in locked position, means for moving said plunger outward to disengage the same from 45 said bolt to permit the latter to return to unlocked position, and a headed element extending through said spring means for limiting the outward movement of said plunger.

50 5. The combination with a lock having a sliding bolt, of a reciprocatory plunger engageable with said bolt to retain the same

in locked position, a spring for moving said 55 plunger into engagement with said bolt, and movable means for rendering said spring inoperative.

60 6. The combination with a lock having a sliding bolt, of a member engageable with said bolt to retain the same in a pre-determined position, yieldable means for moving said member into engagement with said bolt, means for disengaging said member from said bolt, and means engageable with 65 said yieldable means for rendering said member inoperative.

7. The combination with a lock having a sliding bolt, of a member engageable with said bolt to retain the same in a predetermined position, means for moving said member in one direction to engage said bolt, means for moving said member in another direction to disengage said member from 70 said bolt and means engageable with one of the means aforesaid for rendering the same 75 inoperative.

8. The combination with a lock having a movable bolt, of a member engageable with said bolt to retain the same in a pre-determined position, means for moving said member in one direction to engage said bolt, means for moving said member in another direction to disengage said member from 80 said bolt, means engageable with one of the means aforesaid for limiting the movement 85 of the member in one direction, and means also engageable with one of the means aforesaid for limiting the movement 90 of the member in another direction.

9. The combination with a lock having a movable bolt, for a member engageable with said bolt to retain the same in a pre-determined position, a yieldable element for moving said member in one direction to engage 95 said bolt, means connected to the member for moving the same in another direction to disengage said member from the bolt, a swingingly mounted member engageable with said yieldable element for limiting the movement 100 of the member in one direction, and a headed element engageable with said yieldable element for limiting the movement of said member in another direction.

In testimony whereof I affix my signature. 105

NAPOLÉON RANCOUR.
